CLAIM

We claim the ornamental design for head apparel, as shown.

DESCRIPTION

FIG. 1 is a left side elevational view of head apparel showing our new design, the right side is a mirror image;

FIG. 2 is a rear elevational view thereof;

FIG. 3 is a front elevational view thereof;

FIG. 4 is a top plan view thereof;

FIG. 5 is a bottom plan view thereof;

FIG. 6 is a front perspective view in an alternate position;

FIG. 7 is a front perspective view in an alternate position;

FIG. 8 is a front perspective view in an alternate position;

FIG. 9 is a front perspective view in an alternate position; and,

FIG. 10 is a right side perspective view of our design for head apparel, in another configuration as the design might be worn by a user, showing additional ornamental aspects of the design.

The broken line showing of the human form in FIGS. 6, 7, 8, 9, 10 is for illustrative purposes only and forms no part of the claimed design.
